FIG. 1.

FIG. 2.

FIG. 3.

FIG. 4.

FIG. 5.

FIG. 7.

FIG. 6.

FIG. 8.

FIG. 9.

FIG. 1 is a front perspective view of a combination puller and cutting pliers showing my new design;

FIG. 2 is a front perspective view of the pliers in an open position;

FIG. 3 is a rear perspective view thereof;

FIG. 4 is an elevation as seen from the left of FIG. 2;

FIG. 5 is a front elevation of the pliers in a closed position;

FIG. 6 is a right side elevation thereof, in a closed position;

FIG. 7 is a front elevation of the pliers in an open position; and

FIG. 8 is a top plan view of the pliers shown in FIG. 5; and

FIG. 9 is a bottom plan view thereof.

The characteristic features of my design reside in the specific configuration of the jaw members in the combination puller and cutting pliers.

I claim:

The ornamental design for a combination puller and cutting pliers, as shown and described.
